THERMOSTATIC DEVICE

William W. Carson, Jr., Knoxville, Tenn., assignor to The Fulton Sylphon Company, Knoxville, Tenn., a corporation of Delaware

Application May 3, 1930. Serial No. 449,670

45 Claims. (Cl. 236—99)

This invention relates to thermostatic devices and remote controls associated therewith, although as will appear hereinafter, the remote controls of the present invention are capable of use in other relations and in other combinations.

It is an object of this invention to provide a thermostatic device with improved means whereby the operating range of the device may be varied through relatively wide limits.

Another object of this invention is to provide a device of the type just characterized with improved operating means for adjusting the range of operation of said device.

Another object of this invention is to provide a thermostatic device with improved means whereby two or more elements may be operated in sequence.

Another object of this invention is to provide an improved device of the type just characterized with novel means for preventing injury to the parts.

Another object of this invention is to provide a thermostatic device with novel remote control mechanism either for operation of or to be operated by the thermostat.

Another object of the present invention is to provide a device of the type just characterized with improved operating means; also with improved control mechanism.

Another object of this invention is to provide an improved remote control device which is adapted to move the device to be controlled by increments and which may be operated either manually or automatically.

Another object of this invention is to provide a remote control mechanism which is simple in construction, flexible in use, certain in operation and relatively inexpensive to construct and operate.

Another object of this invention is to provide a novel remote control mechanism which is electrically operated and which is economical in the use of electric current; which is equally selective for opposite directions of movement; which assures that the controlled mechanism shall move in the intended direction although the control device is moved rapidly or through a wide range; and which is not rendered inoperative if single points of the selector mechanism become dead.

Another object of this invention is to provide a remote control mechanism with driving mechanism which permits reversal of rotation by movement of a switch in one lead connection, and which uses current only when the remote control mechanism is changing the relationship of the parts.

Another object of this invention is to provide a remote control mechanism with an improved commutator which is simple in construction, which is motor controlled, and which enables a series wound motor to be used with alternating current with the current always flowing in the same direction through the field windings and the armature winding.

Another object of this invention is to provide a remote control mechanism with an improved actuating means which is adaptable either to manual or to automatic operation, and which can be controlled by thermostatic mechanism or by time-controlled mechanism.

Another object of this invention is to provide a remote control mechanism with an improved selective switch device of the mercury contact type.

Another object of the invention is to provide remote control mechanism as hereinbefore characterized in the preceding statements of object in combination with thermostatic mechanism, whether said control mechanism be operated by the thermostatic mechanism or be used to operate thermostatic mechanism.

Other objects will appear as the description of the invention proceeds.

The invention is capable of receiving a variety of mechanical expressions, some of which are shown on the accompanying drawings, but it is to be expressly understood that the drawings are for purposes of illustration only, and are not to be construed as a definition of the limits of the invention, reference being had to the appended claims for that purpose.

Referring in detail to the drawings, wherein the same reference characters are employed to designate corresponding parts in the several figures,—

Fig. 1 is an elevation, partly in axial section, of an embodiment of the present invention;

Fig. 2 is an elevation, partly in section, of a remote control device that may be used in conjunction with the embodiment of Fig. 1;

Fig. 3 is a wiring diagram to illustrate the operation of the remote control device;

Fig. 4 is an end elevation of a selective switch that may be employed in the embodiment of Fig. 3;

Fig. 5 is a more or less schematic view to illustrate another form of selective switch that may be employed in the embodiment of Fig. 3; and

Fig. 6 is a diagrammatic view to show how the remote control mechanism of the present invention may be used to effect the incremental move-

105

110

ment of one or more remote elements the position of which is to be adjusted.

In the embodiment of Fig. 1, wherein the invention is shown as applied to the operation of a valve, as the valve in a gas supply line, 10 designates a valve casing of any suitable size, construction and material, and provided with inlet and outlet connections, one of which is indicated at 11. Within the valve casing is a valve member 12 of any suitable size, construction and material which, for example, may take the form of a double seated balanced valve of large area and small lift.

Attached to the valve casing 10 is a suitable housing 13 for the operating mechanism of the valve member 12. As shown, the valve is of the packless type and the end of the valve member 12 is provided with a recess 14 in which engages a projection 15 on the end wall 16 of a bellows 17, the opposite end of which is attached to an annular member 18 that is suitably secured to the valve casing 10 to form a fluid-tight joint therewith. Said end wall 16 carries a tubular extension 19 which may carry a stop tube 20 and which is threaded interiorly for the attachment thereto of a valve stem 21.

The opposite end of the valve stem 21 is suitably attached, as by a threaded connection 22, to a yoke member 23, the opposite side of which is apertured at 24. Rectilinearly movable in the aperture 24 is a stem member 25 provided, at opposite sides of the yoke section, with suitable limit stops so as to determine and limit the extent of movement of said member 25 in the aperture 24. As shown, the portion of member 25 projecting into the yoke 23 is threaded and carries a nut 26 which acts as one limit stop. Outside of the yoke 23 the member 25 is enlarged so as to provide a shoulder 27 which will engage the outer side of the yoke 23 and limit the inward movement of the member 25 through the aperture 24. The yoke 23 is shown as provided with a socket 28 and the member 25 is shown as provided with a second shoulder 29, and between the bottom of the socket 28 and the shoulder 29 is a coil spring 30 which normally holds the stop 26 against the yoke 23, but which may yield so as to permit the member 25 to be moved inwardly with respect to the yoke until stopped by the engagement of the shoulder 27 therewith.

Suitably attached to the member 25 is a stem 31 which may be guided adjacent its free end, i. e. the lower end as viewed in Fig. 1, by a guide member 32 carried by a tube 33 suitably attached to the yoke 23 as at the socket 28. Telescopically engaged with the tube 33 is a tubular member 34 which, at its opposite end, is suitably attached, as by the thread connection 35, to a socket member 36 mounted on the movable head 37 of a thermostat 38 of any suitable type, size and construction.

Intermediate its ends the tubular member 34 is provided with a shoulder 39 against which is normally engaged a socket member 40 which is recessed at 41 to receive the free end of the stem 31. Interposed between the socket member 40 and the socket member 36 is a coil spring 42 which normally holds the socket member against the shoulder 39 but which may yield to permit movement of the socket member 40 with respect to the tubular member 34 as hereinafter explained. Spring 42 is preferably constructed so as to be somewhat stiffer than the spring 30, so that spring 42 will not yield until after spring 30 has yielded to the extent permitted by the limit stops on the member 25.

Thermostat 38 is mounted in any suitable way so as to subject the same to the medium the temperature of which is to determine the operation of the valve mechanism heretofore described, as for example, air whose temperature is to determine the amount of heating medium flowing past the valve member 12. As shown, the thermostat 38 is of the bellows type and has a deeply corrugated, expansible and collapsible, flexible metal wall 43 which is suitably attached, as by brazing or soldering, to the movable head 37, at one end, and to a stationary end wall 44, at its opposite end. A tubular stop member 45 may be carried by the stationary end wall 44 to limit the contraction of the thermostat, and the thermostat may be charged with a volatile fluid suitable for the temperatures to be controlled through a filling opening 46. Said thermostat is mounted in any suitable way, being shown as having its stationary end wall 44 mounted on or attached to the inwardly directed flanges 47 of a plurality of axially extending arms 48 carried by the flange 49 of a supporting element which may, as respects certain features of this invention, be rigidly attached to the housing 13, but is preferably mounted adjustably thereon as hereinafter explained.

In the form shown, the housing 13 is provided with a tubular extension 50 which has an interior thread 51 of steep pitch. Carried by said extension 50 and provided with an exterior thread 52 coacting with thread 51 is a tubular support 53 attached to or formed integral with the flange 49. Interiorly, said tubular support 53 is provided with a thread 54 and mounted within the bore of said member 53 and coacting with said thread 54, is a nut 55, centrally apertured to permit the passage therethrough of the tube 33 and also provided with suitable apertures 56 to enable adjustment of said nut, as by a spanner wrench. Interposed between the adjustable nut 55 and the movable end wall 37 of the thermostat 38 is a relatively stiff coil spring 57 which in its opposition to the expansion of the thermostat affords a wide range of operation and which can be adjusted as to its tension, by adjustment of the nut 55, so as to predetermine the temperature at which the thermostat, by overcoming the tension of said spring, begins its expansive movement. Inasmuch as said spring 57 and its adjusting means are wholly carried by said support the tension of said spring can be varied independently of the position of said support while said support can be adjusted without affecting the tension of said spring. Tubular support 53 is also provided with a plurality of sockets 58 with which engage a corresponding number of pins 59 carried by a rotatable ring 60 having a suitable bearing in the housing 13. Springs 61 are preferably housed in each of the recesses 58 between the end of the recess and the end of the corresponding pin 59 projecting thereinto. Rotatable ring 60 is provided on its periphery with worm gear teeth 62, and rotatably mounted in the housing 13, in mesh with said teeth 62, is a worm 63 which may be operated manually or by any suitable automatic mechanism to rotate the ring 60 and therefore, through the pins 59, rotate the member 53 to cause the latter to be threaded to a greater or lesser extent into the extension 50 of the housing 13, thereby varying the position of the thermostat with respect to the housing and valve member.

If desired, the ring member 60 may carry a

suitable dial 64 provided with appropriate indicia, so that when these indicia pass a pointer in an aperture or window in the housing 13 (not shown) the position of adjustment of the thermostat with respect to the valve member may be readily determined.

Mounted on the yoke 23 is a switch of any suitable character and construction as for operation of the circuit of a motor or any electrically controlled or operated element and which switch is operated by the member 25. As shown, the switch is of the mercury type, and includes a suitable vessel 66 which carries a pair of contact elements 67 and a body of mercury 68, suitable leads 69 being connected to the contact elements 67. Vessel 66 is mounted in any suitable way, as by clips 70, in a carrier element 71, tiltably mounted at 72 on a projection from the yoke 23. A coil spring 73 attached at one end to said carrier member 71 and at its opposite end to a lug on yoke 23 normally holds the carrier member tilted in the position shown, so that the contained mercury closes the circuit through the contact elements 67. The end of the element 25 is adapted 25 to engage the carrier member 71 and tilt the same about its pivot 72 so that the mercury will leave the contact elements 67. As shown, the end of member 25 engages a pivoted member 74 which has some freedom of movement with respect to the carrier member 71 but which when operated by the member 25 will engage and tilt said member 71 about its pivot 72.

Assuming the parts to be in the relative position shown in Fig. 1, the valve 12 is wide open and the thermostat 38 is in its most contracted position. As the temperature rises a pressure is developed in the thermostat 38 which, when the predetermined temperature is reached, as fixed by the tension of the spring 57, will cause the thermostat to begin its expansive movement against the tension of said spring 57. During the first part of this expansive movement the tubular member 34 will move telescopically with respect to the tube 33 but the stem 31 will not be operated owing to the socket member 40 being spaced from the end of the stem 31. At a predetermined temperature, determined by the position of the support 53 with respect to the casing 13, the socket member 40 will engage the end 50 of the stem 31, and thereafter further expansion of the thermostat will cause movement of the stem 31, the yoke 23 moving with said stem and thereby the valve stem 21 being moved to operate the valve member 12 and close the latter.

When the valve member has engaged its seat, further movement thereof, and of the valve stem 21 and yoke 23, is arrested. If the thermostat continues to expand the spring 30 will begin to yield, permitting the member 25 to be protruded 60 to a greater extent into the yoke 23 until its shoulder 27 finally contacts the same. Prior to contact of the shoulder 27 with the yoke 23, however, the member 25 will tilt the carrier 71 to such a position that the mercury will flow out of 65 contact with the elements 67, and thereby break the circuit through the leads 69. If the thermostat continues to expand after the shoulder 27 has engaged the yoke 23, spring 42 may yield until such time as the movable end wall 27 of the 70 thermostat 38 has engaged the flange 49 and positively arrested any further expansion of the thermostat.

As the temperature falls and the thermostat contracts, the sequence of operation is reversed, the spring 73 tilting the vessel 66 back into the

position to close the circuit through the leads 69 when the spring 30 is permitted to expand and move the member 25 outwardly with respect to the yoke—after the spring 42 has re-engaged the member 40 with the shoulder 39 so that its tension is no longer applied to the stem 31.

While the predetermined tension of the spring 57 fixes the pressure, and therefore the temperature, at which the thermostat begins to expand, the temperature at which the expansion of the thermostat begins to operate the valve member is determined by the distance between the free end of the stem 31 and the bottom of the socket member 40, and this in turn is determined by the adjustment of the tubular support 53 with respect to the casing 13. By rotating the worm 63, either manually or automatically, the ring 60 may be rotated to rotate the support 53 through the pins 59, and, by reason of the steeply pitched threads 51 and 52, cause the support 53 to move inwardly or outwardly with respect to the casing 13 and thereby vary the distance between the elements 31 and 40. As the ring 60 moves with respect to the casing 13 its dial 64 will move with respect to the window in the casing and the indicia 100 carried by said dial will indicate the temperature at which the thermostat will start to move the valve member. It is to be noted that the member 60 can be adjusted without injury to the parts, even though the socket member 40 is already engaged with the stem 31, because if adjustment moves the member 53 further into the casing the socket member 40 may yield with respect to the member 34 and thereby prevent any injury to the parts.

While as respects certain features of this invention the ring 60 may be manually rotated, it not infrequently occurs that the adjustment of said ring should take place from a point remote therefrom, as where the thermostat is disposed in 116 a chamber that should not be entered during some or all of the period when adjustment of the thermostat should be effected. The present invention provides means in combination with a thermostatic device such as so far described 120 whereby the thermostat may be adjusted through any desired increments from a point remote therefrom.

Referring to Figs. 2, 3 and 4, the remote control apparatus to be described is shown as 125 mounted directly on the valve casing 10 and housing 13. As here shown, the ring 60 is provided with pinion teeth and meshing therewith is a pinion 80 carried by the shaft 81 having suitable bearings in the housing 13 and valve casing 130 10, and connected through suitable reducing gears 82 in a housing 83 to a motor shaft 84.

As diagrammatically indicated in Fig. 3, the motor is a series wound motor having a double field coil, the sections 85 and 86 of which are 135 wound in opposite directions and connected in series to the armature 87 which in turn is connected to the main 88. Connected to the field coil 86 is a commutator brush 89 which rides on the periphery of a slip ring 90, and connected to the field coil 85 is a commutator brush 91 which rides on the surface of a slip ring 92. Associated with the rings 90 and 92 are a pair of segments 93 and 94, here shown as semi-circular, although each may be made of less extent. Ring 145 90 is connected to the segment 93 by a lead 95 and ring 92 is connected to the segment 94 by a lead 96. Segments 93 and 94 are separated by insulating blocks 97 and 98, and said rings and segments are mounted on a motor driven shaft 150

99. Cooperating with the segment 94 are a plurality of brushes 100, 101, 102 to 112 inclusive, and each of said brushes is connected by a suitable lead 113 to a corresponding contact point 5 114, 115, 116, to 126 inclusive, of a selector switch which also includes a movable contact arm 127 which is connected by a lead 128 to the main 10 129. The rates of gears in the housing 83 is such that shaft 99 will rotate through an angular 15 distance corresponding to the spacing of the extreme brushes 100 and 112 while the gear 60 is rotated to such an extent as to effect the movement of the thermostat from one extreme position to the other.

15. Assume that contact arm 127 is moved to contact point 119. Current will flow from the main 129 through the lead 128, contact arm 127, contact point 119, and the corresponding lead 113 to brush 105, and thence through segment 94, 20 lead 96, ring 92, brush 91, field coil 86, and armature 87 to main 88. The motor will thereby be driven, and through the reducing gears 82 and shaft 99, the rings and sectors will be rotated in a clockwise direction until the insulating block 25 98 comes under brush 105 and thereby interrupts the circuit. During this period of rotation of the shaft 99, the shaft 81 will be driven to the appropriate extent to adjust the thermostatic mechanism in the manner heretofore described. 30 If the contact arm 127 is now moved forwardly to another contact point, as 122 for example, the motor will again be driven in the same direction and the rings and sectors will be rotated until insulator block 98 comes under the corresponding 35 brush 108.

If contact arm 127 is moved in the opposite direction, the motor will be rotated in the opposite direction correspondingly. Thus, assume that the contact arm is moved from point 122 to 40 point 116. Current will now flow from main 129 through lead 128, contact arm 127, point 116, lead 113, brush 102, segment 93 (which is now under said brush), lead 95 ring 90, brush 89, field coil 85, armature 87 and main 88. As field 45 coil 85 is wound reversely to field coil 86, the motor will rotate in the opposite direction, and the shaft 99 will rotate in the opposite direction, thereby rotating the rings and the segments in the opposite direction, until insulating block 98 50 comes under brushes 102, whereupon the circuit is again interrupted and the parts are left in the new position of adjustment.

In place of the type of slip rings and commutator sector indicated in Fig. 3, the commutator 55 may be constructed as shown in Figs. 2 and 4, where the two segments are formed as two disks 135 and 136 having offset portions and cutaway portions which mate and which are separated by insulation 137. The brushes 89 and 91 are 60 always in contact with the disks 135 and 136 respectively, while the brushes 100—112 will engage one or the other of these disks depending upon the location of the offset in the insulation which corresponds to insulating block 98.

65 It will be noted that the remote control heretofore described permits of the use, with alternating current, of a series wound motor of the double field coil type, and the current always flows through the fields and armature in the same direction. Also current is used only during the period when a change in the adjustment is to be effected, because at all other times the circuit is interrupted by the insulating block 98 underlying the brush which is in circuit with the point 70 engaged by the contact arm 127. The segment

94 need not be 180° in extent, but may be made as much less as desired. Ordinarily it should not extend more than 180°, so as to prevent extreme movement of the contact arm 127 making such a circuit connection as to cause the motor 80 to rotate in the wrong direction from that corresponding with the direction of movement of the contact arm 127.

However, if there is no danger of the contact arm 127 being moved rapidly from one extreme to the other, the segment 94 and brushes cooperating therewith may extend for more than 180°. Such would be appropriate when the contact arm 127 is to be operated by thermostatic or time controlled or other mechanism so that its engagement with the point 114 to 126 is certain to be progressive and gradual. 85 90

The points of the selector switch heretofore described may represent any desired increment of temperature difference, and the temperature increments may be uniform throughout the range of the switch, or they may be non-uniform as shown. For example, the points 114 to 126 inclusive may each represent a change in temperature of one degree at which the thermostat is 100 to begin to start closing of the valve member 12, or the temperature increment may be one degree at the center of the range and two or more degrees near the end of the range, or if desired the temperature increment may progressively increase as the ends of the range are approached, etc. 95 105

While as respects certain features of this invention the selector switch heretofore described may be operated manually, it is within the contemplation of the invention that the selector switch may be operated automatically, as by time controlled mechanism or by thermostatic mechanism, so that as time progresses or a predetermined variation in temperature occurs there shall 110 115 be a program adjustment of the controlled element. Fig. 5 shows a thermostatically operated selector switch. While the thermostat of this figure may operate a selector arm 127 of the type illustrated in Fig. 3, a different type of 120 selector switch is here shown as embodying the present invention.

As here shown, the selector switch takes the form of a mercury switch including a suitable curved vessel 150 carrying a suitable number of 125 contact elements 151, which may be as numerous as those illustrated in Fig. 3, if desired. Vessel 150 is mounted in any suitable way, as by a bracket 152 pivotally mounted at 153, so that it may be tilted to cause a globule of mercury 130 154 to progressively move along the length of the vessel. Carried within the vessel is a contact element 156 which is always in electrical contact with the globule 154, such contact element being connected through lead 157 to any 135 suitable source of current as a series of batteries 158. Leads 159 extend from the several contact elements 151 to commutator brushes, which may be like those described in conjunction with the embodiment of Fig. 3 or they may be those hereinafter described in conjunction with Fig. 6. 140

In order to tilt the vessel 150 automatically, the pivotally mounted bracket 152 is connected through a link 160 to a lever 161 pivoted at 162 in a suitable bracket, and a thermostatic 145 vessel 163 of any suitable character is operatively connected to said lever, or the vessel 163 could be a pressure responsive device, so that as the vessel 163 expands and contracts the vessel 150 will be tilted in accordance with the extent 150

of expansion and contraction thereof. In order that the vessel 163 may be adjusted and the temperature at which it begins to operate the vessel 150 may be predetermined said lever 161 may have connected thereto an adjustable coil spring 164 which at its opposite end, is carried by or operatively connected to a nut 165 on an adjusting screw 166, so that by adjusting said nut, the tension of the spring 164 may be varied and thereby the point at which the vessel begins to operate may be predetermined. To facilitate adjustment, the nut 165 may carry a pointer 167 for cooperation with a suitable scale 168.

In the embodiments so far described the remote control has been used to adjust a thermostat. The embodiment of Fig. 6, however, shows how the remote control, whether operated manually or automatically, may be used to move other elements incrementally, as a damper or shutters. In this embodiment the shaft 99, which as in the embodiment of Figs. 2 or 3 is driven from the motor shaft 84, as by the worm 170 and worm wheel 171, also operates mechanism for operating the element to be controlled. In the form shown, a series of dampers 173, which may be taken as of any suitable means to be controlled, are driven from the shaft 99 in any suitable way, as by chain gearing, pinions or a crank and connecting rod 174. The dampers may thus be opened or closed by small increments as successive points in the selective switch of the remote control are engaged in succession. For example the dampers of a heater may thus be operated by a motor disposed adjacent thereto while the thermostatically operated switch may be disposed in the room or other space the temperature of which is to be controlled.

It will therefore be perceived that novel thermostatic mechanism has been provided which includes means that may be either manually or automatically operated for varying the position of the thermostat with respect to the element to be controlled and which thereby renders the thermostat operative at selected points in a relatively wide range. Moreover this range can be divided up into large or small increments, and the increments may be made equal or unequal or varying in any desired order. The thermostat may also operate a plurality of members in sequence, as the valve and switch, or through the remote control it may move the controlled member or members through a wide range by increments of any desired character. Means have also been provided whereby continued expansion of the thermostat will not result in any injury to the parts.

There has also been provided a remote control mechanism which may be used either for a remote adjustment of a thermostat or for the remote thermostatic actuation of a member to be controlled, which includes improved driving mechanism, and improved control mechanism. Also there has been provided improved selective switch mechanism which may take a variety of forms. Said remote control mechanism is particularly economical because the circuit is used only when an adjustment is to be effected, it permits reversal with a switch in only one of the motor leads, and it enables the use of alternating current in conjunction with a series wound electric motor of the double field coil type with the current flowing through the field and armature windings in the same direction for either direction of rotation. The remote control 75 is equally selective for either direction of rotation,

and it is of such construction that whatever jump is made in the points of the selective switch the motor can only rotate in the direction corresponding with the direction of movement of the switch element. If any point in the selective switch becomes dead the remote control mechanism is not rendered inoperative because all of the remaining points can still be used for effecting adjustment. The remote control system is particularly simple, and yet it is certain in operation, highly efficient, inexpensive to manufacture, install and operate, and flexible in use, enabling it to be employed in a wide variety of relations and combinations and to effect adjustments through small or large ranges and by small or large increments. Said remote control mechanism may also be operated automatically as well as manually, and it lends itself to operation by thermostatic mechanism, time controlled mechanism and other automatic and program devices. While the remote control mechanism has been described in connection with its use in the remote adjustment of a thermostat or whereby a thermostat may control a remote member, it is to be expressly understood that it is within the contemplation of this invention that the remote control may be used for other purposes and in other combinations. Also while the remote control mechanism has been described and illustrated as adjusting thermostatic mechanism by varying the position of the thermostat, said remote control mechanism could be used to adjust a thermostat in other ways as by rotating a nut to predetermine the tension of the spring opposing expansion of the thermostat.

While the embodiments of the invention illustrated on the drawings have been described with considerable particularity, it is to be expressly understood that the invention is not restricted thereto as it is capable of receiving a variety of expressions, some of which will now suggest themselves to those skilled in the art, while changes may be made in the details of construction, arrangement and proportion of parts, and certain features used without other features, without departing from the spirit of the invention.

Reference is therefore to be had to the claims hereto appended for a definition of the limits of the invention.

What is claimed is:

1. In a thermostatic device, in combination with a member to be controlled, a thermostat and operative connections between said thermostat and said member having means for predetermining the temperature at which said thermostat starts to expand, said connections including separable elements, and means for predetermining the extent of separation of said elements, said first named means predeterminately opposing the operative engagement of said elements whereby said thermostat has a predeterminately controlled expansion before said elements engage.

2. In a thermostatic device, in combination with a member to be controlled, a thermostat and operative connections between said thermostat and said member having means for predetermining the temperature at which said thermostat starts to operate said member, said connections including resilient means for opposing expansion of said thermostat throughout its range of expansion and elements normally separated to predetermine the extent of expansion of said thermostat before said thermostat starts to move said member but adapted to be engaged after said

- thermostat has overcome the tension of said resilient means to a predetermined amount.
3. In a thermostatic device, in combination with a member to be controlled, a thermostat and operative connections between said thermostat and said member having means for predetermining the temperature at which said thermostat starts to operate said member, said connections including a pair of elements adapted to be variably spaced and to be engaged and operated by said thermostat only after said thermostat has expanded through a predetermined range, and resilient means for predetermining the temperature at which said thermostat starts to decrease the spacing between said elements.
4. In a thermostatic device, in combination with a member to be controlled, a thermostat and operative connections between said thermostat and said member having means for predetermining the temperature at which said thermostat starts to operate said member, said connections including an element movable with said thermostat, a second element adapted to be spaced therefrom and engaged thereby after a predetermined expansion of said thermostat, said second named element being operatively connected to said member to be controlled, resilient means for predetermining the temperature at which said thermostat starts to decrease the spacing between said elements, means for adjusting said resilient means to predetermined said temperature, and means for predetermining the spacing of said elements.
5. In a thermostatic device, in combination with a member to be controlled, a thermostat and operative connections between said thermostat and said member having means for predetermining the temperature at which said thermostat starts to operate said member, said connections including an element operatively connected to said member, an element movable by said thermostat and adapted to engage and operate said first named element after a predetermined expansion of said thermostat, and resilient means cooperating with said last named element and adapted to yield to permit relative movement between said second named element and the thermostat.
6. In a thermostatic device, in combination with a member to be controlled, a thermostat, operative connections between said member and thermostat including an element operatively connected to said member and an element operatively connected to said thermostat and adapted to engage said first named element after a predetermined expansion of said thermostat, resilient means at all times opposing the engagement of said elements, and means for predetermining the interval of expansion of said thermostat before said elements are operatively engaged.
7. In a thermostatic device, in combination with a member to be controlled, a thermostat, operative connections between said member and thermostat including an element operatively connected to said member and an element operatively connected to said thermostat and adapted to engage said first named element after a predetermined expansion of said thermostat, resilient means for predetermining the initiation and interval of expansion of said thermostat before said elements are operatively engaged, and control means for adjusting said interval.
8. In a thermostatic device, in combination with a member to be controlled, a thermostat, operative connections between said member and thermostat including an element operatively connected to said member and an element operatively connected to said thermostat and adapted to engage said first named element after a predetermined expansion of said thermostat, and means for predetermining the interval of expansion of said thermostat before said elements are operatively engaged including an adjustable support for said thermostat whereby the spacing of said elements may be varied and resilient means carried by said support for opposing the expansion of said thermostat.
9. In a thermostatic device, in combination with a member to be controlled, a thermostat, operative connections between said member and thermostat including an element operatively connected to said member and an element operatively connected to said thermostat and adapted to engage said first named element after a predetermined expansion of said thermostat, and means for predetermining the interval of expansion of said thermostat before said elements are operatively engaged including an adjustable support for said thermostat, means carried thereby for predetermining the temperature at which said thermostat starts to expand, and means for moving said support to adjust said second named element with respect to said first named element to predeterminedly space said elements.
10. In a thermostatic device, in combination with a member to be controlled, a thermostat, operative connections between said member and thermostat including an element operatively connected to said member and an element operatively connected to said thermostat and adapted to engage said first named element after a predetermined expansion of said thermostat, and means to predetermine the interval of expansion of said thermostat before said elements are operatively engaged including a rotatable support within which said thermostat is mounted for expansion and contraction, gearing for rotating said support, and means whereby rotation of said support varies the spacing between said elements.
11. In a thermostatic device, in combination with a member to be controlled, a thermostat, operative connections between said member and thermostat including an element operatively connected to said member, a movable support for said thermostat, means carried by said support for adjusting the temperature at which said thermostat starts to expand, said means being unaffected by the movement of said support, a second element operatively connected to said thermostat and movable therewith, said second named element adapted to engage and operate said first named element after a predetermined expansion of said thermostat, and means for moving said support to vary the position of said elements with respect to each other.
12. In a thermostatic device, in combination with a member to be controlled, a thermostat, operative connections between said member and thermostat including an element operatively connected to said member, a movable support for said thermostat, a second element operatively connected to said thermostat and movable therewith, said second named element adapted to engage and operate said first named element after a predetermined expansion of said thermostat, means carried by said support for controlling the expansion of said thermostat, and a control device for moving said support to vary the position of said elements with respect to each other.
13. In a thermostatic device, in combination with a member to be controlled, a thermostat, operative connections between said member and

- thermostat including an element operatively connected to said member, a movable support for said thermostat, a second element operatively connected to said thermostat and movable therewith, said second named element adapted to engage and operate said first named element after a predetermined expansion of said thermostat, means carried by said support for controlling the expansion of said thermostat, and means for moving said support to variously position said elements with respect to each other including an electric motor and a selective switch. 5
14. In a thermostatic device, in combination with a plurality of members to be controlled, a thermostat, operative connections between said members and thermostat including an element operatively connected to one of said members, a second element adapted to operate another of said members, means normally causing said elements to move as a unit but permitting relative movement thereof after said first named member has been operated, and means for operating said elements from said thermostat, said last named means including relatively separable parts and means to predetermine the spacing of said parts to predetermine the temperature at which said thermostat begins to move said elements. 10
15. In a thermostatic device, in combination with a plurality of members to be controlled, a thermostat, operative connections between said members and thermostat including an element operatively connected to one of said members, a second element adapted to operate another of said members, means normally causing said elements to move as a unit but permitting relative movement thereof after said first named member has been operated, and means for operating said elements from said thermostat, said last named means including relatively separable parts, a movable support for said thermostat, and means to adjust said support to predetermine the spacing of said parts. 15
16. In a thermostatic device, in combination with a member to be controlled, a thermostat, operative connections between said member and thermostat including an element operatively connected to said member, a second element movable with respect to said first element but normally moving therewith, yieldable means normally holding said elements in a predetermined relation, a second member to be controlled operated only by the continued relative movement of one of said elements after the other element has come to rest, and operative connections between said thermostat and said elements. 20
17. In a thermostatic device, in combination with a member to be controlled, a thermostat, and operative connections between said member and thermostat including an element operatively connected to said member, a second element movable with respect to said first element but normally moving therewith, said second element being movable with respect to said first element only after said first element has come to rest, a spring normally holding said elements in predetermined relation, means limiting the relative movement of said elements, and operative connections between said thermostat and elements including a yieldably mounted member which will yield after said second element has reached its limit position. 25
18. In a thermostatic device, in combination with a member to be controlled, a thermostat, operative connections between said member and thermostat including elements operatively connected to said member and thermostat and nor-
- mallly spaced but adapted to engage and constitute an operating connection after said thermostat has expanded a predetermined amount, resilient means for controlling the engagement of said elements, means for adjusting said thermostat with respect to said member, and yieldably mounted means in said connections enabling the adjustment of said thermostat toward said member without operating said member after said connections have been completed. 30
19. In a thermostatic device of the character employing a volatile fluid thermostat operatively connected to a member to be controlled by expansion of said thermostat and having rotatable means for bodily moving said thermostat to any one of a plurality of positions to predetermine the temperature at which it operates said member, remote control means for said adjusting means, said remote control means including an electric motor, a commutator therefor having a plurality of brushes, and a selective switch having as many contact points as there are brushes. 35
20. In a thermostatic device of the character employing a volatile fluid thermostat operatively connected to a member to be controlled by expansion of said thermostat and having rotatable means for bodily moving said thermostat to any one of a plurality of positions to predetermine the temperature at which it operates said member, remote control means for said adjusting means, said remote control means including a series wound electric motor having two reversely wound field coils, a commutator having insulated segments electrically connected to said field coils and a series of brushes cooperating with said segments, and a selective switch for completing the circuit through any one of said brushes. 40
21. In a thermostatic device of the character employing a volatile fluid thermostat operatively connected to a member to be controlled by expansion of said thermostat and having rotatable means movable to any one of several different positions for adjusting said thermostat to predetermine the temperature at which it operates said member, remote control means for said adjusting means, said remote control means including an electric motor and selective switch mechanism in circuit therewith for predetermining the direction and extent of rotation of said motor. 45
22. In a thermostatic device of the character employing a volatile fluid thermostat operatively connected to a member to be controlled by expansion of said thermostat and having rotatable means movable to any one of several different positions for adjusting said thermostat to predetermine the temperature at which it operates said member, remote control means for said adjusting means, said remote control means including an electric motor, a commutator rotatable thereby and electrically connected thereto and including insulated segments and a series of brushes cooperating therewith, and a selective switch in circuit with said brushes for selecting the brush to be in circuit with said motor. 50
23. In a thermostatic device of the character employing a volatile fluid thermostat operatively connected to a member to be controlled by expansion of said thermostat and having rotatable means movable to any one of several different positions for adjusting said thermostat to predetermine the temperature at which it operates said member, remote control means for said adjusting means, said remote control means including an electric motor, a commutator in circuit therewith and rotated thereby and including in- 55

- sulated segments and a series of brushes co-operating therewith, and a selective switch in circuit with said brushes for selecting any one of said brushes to predetermine the direction and extent of rotation of said motor, said commutator including insulation which interrupts the circuit through the selected brush when said motor has moved to the predetermined extent in a predetermined direction.
- 10 24. In a thermostatic device of the character employing a volatile fluid thermostat operatively connected to a member to be controlled by expansion of said thermostat and having rotatable means movable to any one of several different 80 15 positions for adjusting said thermostat to predetermine the temperature at which it operates said member, remote control means for said adjusting means, said remote control means including a series wound electric motor having two 85 20 oppositely wound field coils, a commutator electrically connected thereto and driven thereby and including a series of brushes and a circuit interrupting element for successively engaging the same to predetermine the direction and extent of rotation of said motor, and a selective switch having as many contact points as there 90 25 are brushes in said commutator.
25. In a thermostatic device of the character employing a volatile fluid thermostat operatively connected to a member to be controlled by expansion of said thermostat and having rotatable means movable to any one of several different 100 30 positions for adjusting said thermostat to predetermine the temperature at which it operates said member, remote control means for said adjusting means, said remote control means including an electric motor, a commutator electrically connected thereto and including a series of brushes for predetermining the direction and extent of rotation of said motor, and a selective 105 35 switch having as many contact points as there are brushes in said commutator and including a movable vessel carrying a plurality of contact points and a movable element actuated by the 110 40 movement of said vessel for selectively closing the circuit through any one of said contacts.
26. In a thermostatic device of the character employing a volatile fluid thermostat operatively connected to a member to be controlled by expansion of said thermostat and having rotatable means movable to any one of several different 115 45 positions for adjusting said thermostat to predetermine the temperature at which it operates said member, remote control means for said adjusting means, said remote control means including an electric motor, a commutator electrically connected thereto, and including a series of brushes for selectively determining the direction and extent of rotation of said motor, a selective 120 50 switch for selecting the brush to be in circuit with said motor, and automatic means for operating said switch.
27. In a thermostatic device of the character employing a volatile fluid thermostat operatively connected to a member to be controlled by expansion of said thermostat and having rotatable means movable to any one of several different 125 55 positions for adjusting said thermostat to predetermine the temperature at which it operates said member, remote control means for said adjusting means, said remote control means including an electric motor, a commutator in circuit therewith and including a series of brushes for predetermining the direction and extent of 130 60 rotation of said motor, a selective switch for selecting the brush to be in circuit with said motor, and automatic means for operating said switch.
28. In a remote control mechanism, in combination with means to be controlled, a series wound electric motor operatively connected thereto and having two oppositely wound field coils, a commutator including insulated segments respectively connected to said field coils and a series of brushes cooperating with said segments, and means for predetermining the brush of said series to be in circuit with said motor, said last named means including a tiltable vessel including a plurality of contact points and an element movable therein upon tilting of said vessel to predetermine the contact through which the circuit 135 65 is closed to said motor.
29. In a remote control mechanism, in combination with means to be controlled, a series wound electric motor operatively connected thereto and having two reversely wound field coils, a commutator in circuit therewith and rotated thereby, said commutator including insulated segments respectively connected to said field coils and a series of brushes cooperating with said segments, means for placing any one of said brushes in circuit with said motor, an insulating means for interrupting the circuit through the selected brush when said motor has rotated in the selected direction to the selected amount, and a selective switch for predetermining the brush to be in circuit with said motor, said switch including a tiltably mounted vessel carrying a plurality of contact elements and a movable globule of mercury positioned in contact with any of said contact elements by the tilting of said vessel. 140 70
30. In a remote control mechanism, in combination with means to be controlled, a series wound electric motor operatively connected thereto and having two oppositely wound field coils, a commutator including insulated segments respectively connected to said field coils, and a series of brushes cooperating with said segments, means for selecting the brush to be in circuit with the motor, and means carried by said segments for interrupting the circuit through the selected brush when said motor has rotated to the predetermined amount in the predetermined direction, said segments being formed by disks having mating offset and undercut sections. 145 75
31. In a remote control mechanism, in combination with means to be controlled, an electric motor operatively connected thereto, a commutator electrically connected to said motor and rotatable thereby, said commutator including two disks each having an offset and an undercut portion, insulation separating said disks, a pair of brushes contacting said disks and electrically connected to said respective field coils, and a series of brushes cooperating with said disks and adapted to be successively engaged by said insulation as said commutator rotates in one direction or the other. 150 80
32. In a thermostatic device of the character employing a volatile fluid thermostat operatively connected to a member to be controlled by expansion of said thermostat and having means movable to any one of a multiplicity of points to adjust the thermostat and vary the temperature at which said member is operated, an electric motor operatively connected to said means, a commutator for determining the extent of direction and rotation thereof, and a selective switch electrically connected to said commutator and including a tiltable vessel carrying a plurality of contact points, means in said vessel for selec- 155 85

tively engaging said contact points when said vessel is tilted, and means for tilting said vessel.

33. In a thermostatic device of the character employing a volatile fluid thermostat operatively connected to a member to be controlled by expansion of said thermostat and having means movable to any one of a multiplicity of points to adjust the thermostat and vary the temperature at which said member is operated, an electric motor operatively connected to said means, a commutator for determining the extent of direction and rotation thereof, and a selective switch electrically connected to said commutator and including a member carrying a plurality of contact points, means for selectively engaging said contact points, and automatic means for progressively moving said last named means.

34. In a thermostatic device of the character employing a volatile fluid thermostat operatively connected to a member to be controlled by expansion of said thermostat and having means movable to any one of a multiplicity of points to adjust the thermostat and vary the temperature at which said member is operated, an electric motor operatively connected to said means, a commutator for determining the extent of direction and rotation thereof, and a selective switch electrically connected to said commutator and including a member carrying a plurality of contact points, means for selectively engaging said contact points, and a thermostat operatively connected to said switch to predetermine the contact closed in accordance with the temperature of the medium to which said thermostat is subjected.

35. In a thermostatic device of the character employing a volatile fluid thermostat operatively connected to a member to be controlled by expansion of said thermostat and having means to be moved through successive increments to adjust said thermostat to any one of several positions, a motor driven shaft for operating said means, and a commutator for controlling the direction and extent of rotation of said motor, said commutator including a series of brushes, a selective switch for predetermining the brush to be in circuit with said motor, and automatic means for operating said switch.

36. In a thermostatic device of the character employing a volatile fluid thermostat operatively connected to a member to be controlled by expansion of said thermostat and having means to be moved through successive increments, to adjust said thermostat to any one of several positions, a motor driven shaft for operating said means, and a commutator for controlling the direction and extent of rotation of said motor, said commutator including a series of brushes, a selective switch for predetermining the brush to be in circuit with said motor, and a thermostat for operating said switch.

37. In a thermostatic device of the character employing a volatile fluid thermostat operatively connected to a member to be controlled by expansion of said thermostat and having means to be moved through successive increments to adjust said thermostat to any one of several positions, a motor driven shaft for operating said means, and a commutator for controlling the direction and extent of rotation of said motor, said commutator including a series of brushes, and a selective switch for predetermining the brush to be in circuit with said motor, said switch including a tiltable curved vessel carrying a plurality of contact points and a globule of mercury

adapted to successively engage said contact points as said vessel is progressively tilted.

38. In a thermostatic device of the character employing a volatile fluid thermostat operatively connected to a member to be controlled by expansion of said thermostat and having a member to be moved by successive increments to adjust said thermostat to any one of several positions, a series wound electric motor having two oppositely wound field coils, a commutator electrically connected to said motor and rotated thereby, said commutator including insulated segments electrically connected to the respective field coils and a series of brushes cooperating with said segments, selective switch mechanism for predetermining the brush in circuit with said motor, and a thermostat for operating said selective switch.

39. In a remote control mechanism, in combination with means to be moved by successive increments, an electric motor operatively connected thereto and including two reversely wound field coils, and a commutator driven by said motor, said commutator including a series of brushes and a pair of segments cooperating with said brushes and separated by insulation movable into contact with any of the brushes of said series, and electrical connections between said segments and the respective field coils.

40. In a thermostatic device of the character having a volatile fluid thermostat operatively connected to a member to be controlled by expansion of said thermostat and having rotatable means movable to any one of several different positions for adjusting said thermostat to predetermine the temperature at which it becomes operative to actuate said member, said means including a motor, a control device movable in either direction through a series of points corresponding with desired operating temperatures, and means interposed between said control device and said motor for controlling the latter whereby said motor operates said adjusting means in conformity with the selected point of said control device.

41. In a thermostatic device of the character having a volatile fluid thermostat operatively connected to a member to be controlled by expansion of said thermostat and having rotatable means movable to any one of several different positions for adjusting said thermostat to predetermine the temperature at which it becomes operative to actuate said member, said means including a remote control device, and means interposed between said device and said thermostat whereby progressive increments of movement of said control device produce progressive increments of adjustment in said thermostat.

42. In a thermostatic device of the character having a volatile fluid thermostat operatively connected to a member to be controlled by expansion of said thermostat and having rotatable means movable to any one of several different positions for adjusting said thermostat to predetermine the temperature at which it becomes operative to actuate said member, said means including a remote control device, a motor for adjusting said thermostat, and means connecting said device and motor and operative to produce successive increments of movement of said member in either direction in response to successive increments of movement of said device in a corresponding direction.

43. In a thermostatic device of the character having a volatile fluid thermostat operatively

connected to a member to be controlled by expansion of said thermostat and having rotatable means movable to any one of several different positions for adjusting said thermostat to pre-
5 determine the temperature at which it becomes operative to actuate said member, said means including a remote control device movable through successive increments, an electric motor operatively connected to said thermostat, and
10 a motor driven means electrically connected to said remote control device and operative to effect rotation of said motor to adjust said thermostat by increments corresponding to the direction and extent of movement of said remote control device.
15 44. In a thermostatic device of the character employing a volatile fluid thermostat operatively connected to a member to be controlled by expansion of said thermostat and a rotatable member for adjusting said thermostat to pre-
20 determine the temperature at which it becomes operative to actuate said member, means for adjusting said member to any one of several different positions including a motor, a remote

control device movable through successive increments, a motor driven means electrically connected to said remote control device and operative to effect rotation of said motor and adjustment of said member by increments corresponding to the direction and extent of movement of said remote control device, and thermostatic means for operating said remote control device. 80

45. In a thermostatic device, in combination with a member to be controlled, a thermostat and operative connections between said thermostat and said member having resilient means for predetermining the temperature at which said thermostat starts to expand, said connections including separable elements, and means for predetermining the extent of separation of said elements, said resilient means predeterminately opposing the operative engagement of said elements and being unaffected by said means for predetermining the extent of separation of said elements. 85 90 95
